FIG. 2 is a top, front, left-side perspective view of the “sleeve” configuration of the re-closeable package shown in FIG. 1;

FIG. 3 is a top, front, right-side perspective view of the “sleeve” configuration of the re-closeable package shown in FIG. 1, shown with exemplary consumable items;

FIG. 4 is a top, front, left-side perspective view of the “sleeve” configuration of the re-closeable package shown in FIG. 1, shown with exemplary consumable items;

FIG. 5 is a bottom, back, left-side perspective view of the “sleeve” configuration of the re-closeable package shown in FIG. 1;

FIG. 6 is a bottom, back, right-side perspective view of the “sleeve” configuration of the re-closeable package shown in FIG. 1;

FIG. 7 is a top, front, right-side perspective view of the “sleeve” configuration of the re-closeable package shown in FIG. 1, shown from a steep overhead perspective;

FIG. 8 is a top, front, left-side perspective view of the “sleeve” configuration of the re-closeable package shown in FIG. 1, shown from a steep overhead perspective;

FIG. 9 is a front view of the “sleeve” configuration of the re-closeable package shown in FIG. 1;

FIG. 10 is a back view of the “sleeve” configuration of the re-closeable package shown in FIG. 1;

FIG. 11 is a left-side view of the “sleeve” configuration of the re-closeable package shown in FIG. 1;

FIG. 12 is a right-side view of the “sleeve” configuration of the re-closeable package shown in FIG. 1;

FIG. 13 is a top view of the “sleeve” configuration of the re-closeable package shown in FIG. 1;

FIG. 14 is bottom view of the “sleeve” configuration of the re-closeable package shown in FIG. 1;

FIG. 15 is a top, front, right-side perspective view of a “closed” configuration of the re-closeable package shown in FIG. 1;

FIG. 16 is a top, front, left-side perspective view of the “closed” configuration of the re-closeable package shown in FIG. 15;

FIG. 17 is a bottom, back, left-side perspective view of the “closed” configuration of the re-closeable package shown in FIG. 15;

FIG. 18 is a bottom, back, right-side perspective view of the “closed” configuration of the re-closeable package shown in FIG. 15;

FIG. 19 is a front view of the “closed” configuration of the re-closeable package shown in FIG. 15;
FIG. 20 is a back view of the “closed” configuration of the re-closeable package shown in FIG. 15;
FIG. 21 is a left-side view of the “closed” configuration of the re-closeable package shown in FIG. 15;
FIG. 22 is a right-side view of the “closed” configuration of the re-closeable package shown in FIG. 15;
FIG. 23 is a top view of the “closed” configuration of the re-closeable package shown in FIG. 15;
FIG. 24 is a bottom view of the “closed” configuration of the re-closeable package shown in FIG. 15;
FIG. 25 is a top, front, right-side perspective view of a “re-opened” configuration of the re-closeable package shown in FIG. 1;
